(57) **CLAIM**

The ornamental design for a positioning bed pad, as shown and described.

DESCRIPTION

FIG. 1 is a front perspective view of a positioning bed pad showing my new design;

FIG. 2 is a rear perspective view thereof;

FIG. 3 is a front elevational view thereof; and,

FIG. 4 is a rear elevational view thereof.

The broken lines in the figures represent stitching that forms part of the claimed design.
